ATTORNEY

not possible to knit a reversed pattern in the fabric using the same jacks, i. e. a pattern which begins with the uppermost jack butts, for that would require that the cam descend from one patterning level to the next which is possible and also require that the cam be raised to initial position at the rate of five butt levels at each step which is physically impossible for the link-chain method of moving the cam. While the chain can permit the lowering of the cam five butt levels at one step it is incapable of raising the cam the same distance in one step. Accordingly when it has been desirable to reverse the design pattern in the fabric it has been necessary to install a completely new set of jacks in the machine with the pattern reversed in the butt set-up.

It will thus be understood that not only has the patterning capacity of the machine been undesirably reduced from twenty-five steps to twenty steps but also that the productive capacity is necessarily curtailed during the time required to install a new set of jacks for reversed patterns. In addition to these undesirable features there is the matter of the expense of the new jacks and the labor of installing them.

All of the above objectionable features are obviated by the present invention wherein a single butt-actuating cam is adapted to act upon all twenty-five butts of the finger actuating jacks to retain the full patterning capacity of the machine; is adapted to act upon successive butt levels step-by-step beginning with either the uppermost or the lowermost butt and to return to its initial position without operating any of the butts, so that reversed patterns may be made upon the same set of jacks.

In the portion of the machine of the Larkin patent shown in the present drawings there is provided a rotary plate 10 which rotates counterclockwise, Fig. 2, and a stationary finger cylinder 11 having slots 12 in which pivotally mounted fingers 13 and operating jacks 14 having frangible butts 15 are mounted, all in a manner as explained in the said patent. The apparatus of the present invention indicated generally at 16 is supported in depending position relative to the rotary plate 10 by means of the spaced parallel posts 17 and 18 which extend into suitable apertures in the plate, being held there by suitable set screws such as 19 shown holding the post 18. The lower ends of posts 17 and 18 are secured to a bob cam 20 by means of screws 21, 21 extending through the cam 20 and into the posts. The edge of cam 20 serves to return the fingers 13 to withdrawn position as shown in Fig. 1 while its upper surface serves as a stop for and as means to move the pin 22 vertically as it moves toward the cam 20. The pin 22 is positioned for vertical movement in a suitable bearing aperture 23 formed in the bracket 24 of irregular shape which in turn is positioned for vertical movement on the posts 17 and 18 which are inserted in suitable bearing apertures 25 and 26 in the bracket 24. In order to move the bracket 24 and its associated parts up and down on the posts it is provided with a rearwardly extending pin supported roller 27, adjacent the post 18, which is adapted to enter between the out-turned jaws 28, 28 of the vertically movable control member 29 and be raised or lowered thereby. The control member 29, which does not rotate, is progressively movable up or down step-by-step a distance corresponding to the distance it is desired to move the bracket 24 by means of suitable connections to links of suitable height on a progressively movable pattern chain (not shown) so that when the roller 27 of the rotating bracket 24 enters and rides up upon one or the other of the leading curved portions of the jaws 28, 28, it will be moved either up or down the desired distance during a short portion of one revolution of the machine depending upon whether the control member 29 was moved up or down in time to move the bracket in that one revolution. It will of course be understood that the control member 29 may remain at one level for one or more revolutions of the machine and that for those revolutions of the machine the bracket will remain unmoved vertically. In this way by means of links of suitable height on the chain, the bracket 24 may remain stationary or be moved a step at a time in either direction which step may be the distance from one butt level to the next butt level or may be greater than this distance depending upon the pattern set-up of the machine. The bracket 24 may be frictionally held against accidental displacement by means of friction plug 30, spring 31, and adjustable screw 32 set in the bracket 24 and which exerts

a restraining force against post 18, as shown in dotted lines in Fig. 1.

In order to actuate the butts 15 there is provided the member 33 having the undercut curved butt-actuating camming edge 34, the member 33 being positioned in a groove in and pivotally mounted at one of its ends on a suitable flat portion of bracket 24 adjacent the post 17 by means of the bearing stud 35 so that the member 33, which may be termed a swing cam, is adapted to be moved toward the butts 15 into active butt-actuating position and away from the butts 15 into inactive non-butt-actuating position in which latter position the cam 33 comes to rest against the bottom of the groove cut in the bracket 24 acting as a stop member. A tension spring 36 suitably attached to the free end of the swing cam 33 and to a pin 37 on bracket 24 urges the cam to its outer inactive position. The means which positions cam 33 in its two positions is the pin 22 shown alone in Figs. 7 and 8 in its two operating positions, one being the reverse of the other for the purpose of causing the cam 33 to reverse its action when it is desired to reverse the position of the design pattern in the fabric. The pin 22 is positioned, in either of the positions of Figs. 7 or 8, for limited vertically sliding movement in aperture 23 of the bracket 24 wherein the rounded rear edge of cam 33 is adapted to come into contact with certain of the peripheral portions of the pin 22 depending upon the position desired for the cam 33. The pin 22, itself circular in cross-section at any point along its operative length so that it will be equally effective in any angular position, has the centrally disposed section 38 of a certain diameter and which is slidably disposed in aperture 23 of the bracket, with adjacently disposed sections of reduced diameter 39 and 40, the section 40 being of a lesser diameter than the section 39 and followed by a section 41 of the same diameter as section 39, while the section 39 is followed by a section 42 of the same diameter as section 40, the sections 41 and 42 being respectively followed by adjacently disposed larger diameter sections 43, 44 having flat outer surfaces 45 and 46.

When the pin 22 is positioned in the upright position of Fig. 8 in the bracket 24, see Figs. 1, 4, 5 and 6, and when the bracket is in its lowermost position, Figs. 1, 4, 5, the end face 45 of the pin rests upon the upper face of bob cam 20 and causes the pin section 39 to be aligned and in contact with the rear edge of swing cam 33 so that the latter is pivotally moved toward the finger cylinder 11 sufficiently to be in position to actuate the butts 15, the cam 33 being urged by spring 36 against the section 39 which retains the pin 22 in this vertical position. In this position of the parts, Figs. 1, 5, the bracket 24 is ready to be moved upwardly step-by-step in accordance with and by the action of the control member as the latter is positioned by the pattern chain (not shown). If the step-by-step movement is from one butt level to the next, the cam 33 will in turn actuate the pattern arranged butts at all twenty-five levels. After the last upper butt level has been reached the bracket 24 is given an additional upward movement, Fig. 6, dotted line position of Fig. 4, during which the upper surface 46 of the pin comes into contact with and is depressed by an overlying projecting stud 47 set in collar 48 adjustably secured to post 17, this downward movement of the pin 22 relative to the bracket 24 causing pin section 39 to pass below cam 33 and be replaced by the smaller diameter pin section 42 of sufficiently small diameter as to permit the swing cam 33, by action of spring 36, to be moved sufficiently outwardly from the needle cylinder to miss the butts and to be in inactive or non-butt-actuating position. With the swing cam 33 in this outer position the bracket may be safely lowered step-by-step at the rate of one or more butt levels per step by the action of control member 29 to the lowermost position of Figs. 1, 4, 5, 6 without any danger of actuating the butts. As the bracket is given its last downward movement the face 45 of the pin comes into contact with and is moved upwardly by the bob cam 20 causing pin section 42 to rise above cam 33 and be replaced by section 39, thereby moving the swing cam outwardly into active position preparatory to another raising of the bracket for another pattern in the fabric during the continued knitting thereof.

When it is desired to reverse the direction of the pattern design in the fabric it is merely necessary to reverse the position of pin 22 in bracket 24 from the position of Fig. 8 to that of Fig. 7 as shown in Fig. 3. In reversing

the pattern the butts on the jacks are operated from their top level toward the bottom level instead of from the bottom level upward so that the bracket 24 must first be at the uppermost butt level with the swing cam in operative position. This is shown in dotted lines in Fig. 3 where pin 22, having been depressed by stud 47, has its pin section 41 in operative relation to the swing cam 33. From this dotted line position the bracket moves downwardly step-by-step in the manner explained until it reaches the full line position of Fig. 3 whereupon the face 46 of pin 22 comes into contact with and is raised by cam plate 20 so that pin section 41 is raised above the swing cam and is replaced by section 40 which permits the swing cam 33 to be moved outwardly to inactive position in the manner already explained. With cam 33 in the inactive position, the bracket may be safely raised to the dotted line position of Fig. 3 preparatory to knitting the next reversed pattern design in the fabric, the stud 47 acting upon the pin 22, as the bracket is raised, to lower the same so that pin section 41 is in position behind the swing cam to move it to active butt-actuating position.

It will be understood therefore that the present invention provides an improved pattern control apparatus in which a single cam is adapted to act upon the vertically disposed circular series of projecting butts of operating jacks of any type in a manner which permits the use of the full number of the butts for patterning purposes in the fabric and which permits of the actuation of the jacks beginning with the butts at either end of the jacks so that with a single set-up of jacks the design pattern being knit in the fabric may be readily and easily reversed in relation to the direction of the knitting of the fabric itself.

We claim:

1. In a circular knitting machine provided with a series of circularly arranged control instrumentalities having a number of circular series of actuating butts arranged at a number of closely adjacent levels, means to actuate said butts comprising a cam rotatable relative to said instrumentalities, said cam being adapted to move step-by-step in one direction transversely of said series of butt levels from a terminal butt level to each of the adjacent butt levels in turn while in butt actuating position and to move in the opposite direction to return to said terminal butt level while in non-butt actuating position, and self-acting means adapted to move said cam to non-butt actuating position while said cam is making its final movement in said one direction.

2. In a circular knitting machine provided with a series of circularly arranged jacks having a pattern series of butts arranged at a number of levels, means to actuate said jacks so that the full capacity of the butts may be

used for patterning purposes, said means comprising a cam rotatable relative to said jacks and movable step-by-step from one terminal butt level to the opposed terminal butt level and back again, said cam being automatically placed in butt-actuating position by its movement in one direction and being automatically placed in non-butt-actuating position by its movement in the opposite direction.

- 5 3. In a circular knitting machine provided with a series of circularly arranged jacks having a pattern series of butts arranged at a number of levels, means to actuate said jacks so that the full capacity of the butts may be utilized for patterning purposes, said means comprising a cam rotatable relative to said jacks and movable lengthwise thereof in turn from each end terminal butt level to the opposed terminal butt level, and self-acting means acting upon said cam at one end of its lengthwise movement to place said cam in butt-actuating position and acting upon said cam at the other end of its lengthwise movement to place said cam in non-butt-actuating position.
- 10 4. In a circular knitting machine as set forth in claim 2, self-acting means automatically operative upon said cam to place the latter in its defined positions during its final movements in opposite directions.
- 15 5. In a circular knitting machine as set forth in claim 3 in which said cam is pivotally mounted for movement toward said jacks to be in butt-actuating position and away from said jacks to be in non-butt-actuating position, and in which the said means provided to place the said 20 cam in each of said positions is self-actuated.
- 25 6. In a circular knitting machine as set forth in claim 3 in which the means acting upon said cam is self-acting in the form of a reversely positionable lengthwise displaceable pin having sections of different diameters which are 30 adapted to be placed so as to maintain said cam in each of said positions, said pin being adapted to be automatically displaced vertically in opposite directions at each end of the lengthwise travel of said cam.
- 35 7. In a circular knitting machine as set forth in claim 40 1 in which said self-acting means is adapted to move said cam to butt-actuating position while said cam is making its final movement in said opposite direction.
